UNITED STATES PATENT OFFICE.

HENRY RAYMOND, OF OTTAWA, ONTARIO, CANADA.

RAZOR ATTACHMENT.

1,299,382.

Specification of Letters Patent.

Patented Apr. 1, 1919.

Application filed December 29, 1917. Serial No. 209,593.

To all whom it may concern:

Be it known that I, HENRY RAYMOND, a subject of the King of Great Britain, residing at Ottawa, in the Province of Ontario and Dominion of Canada, have invented new and useful Improvements in Razor Attachments, of which the following is a specification.

This invention relates to an attachment 10 for razors and particularly to that type of attachment which is intended for application to the blade of the razor to prevent a person using the razor from cutting their face with the blade.

15 The primary object of the invention is to provide an inexpensive and durable attachment of this character which is so constructed that it may be applied to and used in connection with the blades of the various makes of razors now in use irrespective of the width and length of the razor blade.

With these and other objects in view, the invention resides in the novel combination and arrangement of parts, which will be 20 25 hereinafter described and particularly pointed out in the claims.

The preferred embodiment of the invention has been illustrated in the accompanying drawings, although no restriction is 30 necessarily made to the precise details of construction therein shown, as changes, alterations, and modifications within the scope of the claims may be resorted to when desired.

35 In the drawings:—

Figure 1 is a view in side elevation of razor blade and a portion of the handle connected therewith, with the blade of the razor having mounted thereon an attachment constructed in accordance with the invention.

Fig. 2 is a view in elevation looking at the side of the razor blade opposite that shown in Fig. 1.

45 Fig. 3 is a top plan view of Fig. 1.

Fig. 4 is a vertical transverse section on the line 4—4 of Fig. 1.

Fig. 5 is a perspective view of one of the guards.

50 Fig. 6 is a perspective view of one of the clamps for use in connection therewith.

Like characters of reference denote corresponding parts throughout the several views in the drawing.

55 Referring now to the drawing in detail

wherein a portion of a razor handle A is shown having mounted upon the blade B thereon an attachment C constructed in accordance with the invention.

The attachment C includes a plurality of 60 clamps 10 which are mounted upon the back of the blade B. The clamps 10 which are preferable three in number are formed from any resilient material suitable for the purpose with each clamp comprising a substantially U-shaped yoke 11 which overlies the back of the blade B and has formed at the outer ends of the arms thereof lugs 12 which extend beneath the back of the blade B. Extending outwardly from the free ends of 70 the arms of the yoke 11 in line with the lugs 12 are fingers 13 which are curved upwardly and toward the arms of the yoke 11 for a purpose which will hereinafter appear.

The yokes 11 are arranged within guards 75 14 with each guard formed from a strip of resilient material which is folded upon itself as shown to provide the guard with an outwardly curved arm 15 and an inwardly curved arm 16 which is of greater length 80 than the arm 15. Formed in the arms 15 and 16 are aligned openings 17 through which project the curved portions of the fingers 13 on the yoke 11 which is arranged within the guard, so that the fingers 13 on the yokes 85 serve as a yieldable seat for the guards.

Each guard 14 has formed therein above the yoke 11 a threaded opening 18 beyond which extends a threaded stem 19 on the yoke 11 upon which the guard is mounted, 90 said stem having threadedly engaged therewith a nut 20 which is adapted to bear on the guard 14 whereby, through the adjustment of the nut on the stem 19 the guard may be moved transversely of the blade B 95 against the influence of the fingers on the yoke 11. The arms 16 on the guards 14 extend below the cutting edge of the blade B and have formed therein a transversely extending row of notches 21.

The guard 14 which is arranged centrally of the blade B has formed on the arm 16 thereof a transversely extending sleeve 22 in which is mounted to turn a rod 23 which extends beyond the sides of the guard 14 105 and has formed thereon right and left hand threads for engagement with the threads within the sleeves 24 on the arms 16 of the yokes 11 upon opposite sides of the yoke which is arranged centrally of the blade B. 110

The rod 23 has a head at one end thereof, so that by turning the rod 23 the guards 14 adjacent the ends of the blade B may be moved toward the guard which is arranged centrally of the blade against the influence of coiled expansion springs 25 carried by the rod 23 and interposed between the arms 16 of the guards 14.

Through the above described manner of connecting the guards with the yokes 11 and with each other it is apparent that the guards may be adjusted both longitudinally and transversely of a razor blade when mounted thereon to permit the attachment to be used in connection with razor blades of different lengths and widths.

The guards 14 which are arranged adjacent the ends of the blade B have formed in the top thereof an eye 26 through which is passed a combined guide and brace rod 27 secured at its central portion to the top of the guard 14 which is arranged centrally of the blade B.

When it is desired to apply an attachment constructed in accordance with the invention to the blade of a razor, the blade is passed through the guards 14 to engage the yokes 11 with the back of the blade after which by operating the rod 23 the yokes at the ends of the attachment may be adjusted with relation to the ends of the blade B. The nuts 20 are now adjusted on the stems 19 to adjust the yokes with relation to the cutting edge of the blade B and after such adjustment of the yokes the razor is ready for use.

From the foregoing description taken in connection with the accompanying drawing it is apparent that an attachment for razor blades has been provided which though simple in construction is highly efficient for the purpose set forth.

Having thus described the invention, what is claimed as new, is:—

1. A razor attachment comprising a plurality of clamps, and adjustably connected guards adjustably mounted on said clamps. 45

2. A razor attachment comprising a plurality of resilient clamps, adjustably connected guards movably mounted on said clamps, and means operable to move said guards on said clamps. 50

3. A razor attachment comprising a plurality of resilient clamps, guards movably mounted on said clamps, means on said clamps contacting with said guards operable to move said guards on said clamps, and a rod on which said guards are adjustably mounted. 55

4. A razor attachment comprising a plurality of clamps, resilient fingers on said clamps, guards within which said clamps are arranged, seats on said fingers, stems on said clamps extending beyond said guards, nuts adjustably mounted on said stems contacting with said guards, and a rod with which said guards are adjustably connected. 60

5. A razor attachment comprising a plurality of clamps, adjustably connected guards adjustably mounted on said clamps, eyes on some of said clamps, and a combined guide and brace bar on the other of said clamps 70 passing through said eyes.

6. A razor attachment comprising a rod having a right and left hand thread thereon, 75 a guard having a sleeve thereon through which said rod is passed, a combined guide and brace bar on said guard, other guards mounted to slide on said bar having sleeves threadedly engaged with the threads on said rod, and resilient clamps upon which said guards are adjustably mounted.

In testimony whereof I affix my signature.

HENRY RAYMOND.
